(57) **CLAIM**

The ornamental design for a decorative conductive cord, as shown and described.

DESCRIPTION

FIG. 1 is a perspective view of the first embodiment of the decorative conductive cord with light elements along its length;

FIG. 2 is a side view thereof;

FIG. 3 is an end view thereof;

FIG. 4 is an end view thereof;

FIG. 5 is a perspective view of the second embodiment of the decorative conductive cord with light elements along its length; and,

FIG. 6 is a side view thereof.

The ornamental design which is claimed is shown in solid lines in the drawings. In the drawings, the broken lines are for the purpose of illustrating environment only and form no part of the claimed design.
